UNITED STATES PATENT OFFICE

LOUIS JUDELSON, OF NEW YORK, N. Y.

WALL DRIER

Application filed July 8, 1927. Serial No. 204,248.

This invention relates to clothes driers and particularly to the type known as wall driers used in the kitchens and kitchenettes of small apartments where available space for such purposes is very limited and it is necessary 5 to elevate the garments overhead during the drying process thereof.

Probably the most widely used overhead wall drier is a device comprising a rack suspended from the ceiling by a block and tackle arrangement and consisting ordinarily of a rectangular frame between the ends of which are carried a series of spaced rods and bars to hold the clothes in hanging position. The 10 rack is of course lowered and hung with the wet garments and then elevated to remain adjacent the ceiling during the evaporation of the moisture from the clothes. As a result 15 the ceiling over the drier gathers the moisture from the wet clothes and is soon ruined.

As an improvement over the rack type wall drier, I have devised a drier which has all the advantages of the ordinary drier and which is hung and operated from a side wall 20 and capable of being swung about so as to bring the clothes in front of an open window during the drying operation and against the side wall in an out of the way position when not in use. With this in view the object of 25 this invention is to provide an adjustable wall drier which, because of its particular construction and arrangement, is very efficient and inexpensive to manufacture. I accomplish this object by means of the apparatus 30 illustratively exemplified in the accompanying drawings, in which, Figure 1 is a side elevational view of the invention showing some parts in section and others in dotted positions; Figure 2 is a front elevational view 35 of the same; Figure 3 is a sectional view of the lower end of the wall drier and the pulley arrangement for winding and unwinding the cable from which the drier proper is suspended; Figure 4 is a substantially trans- 40 verse sectional view of the pulley device taken on lines 4-4 of Figure 3; Figure 5 is a modification of the means used to support and elevate the drier board; Figure 6 is a front elevational view of the same; and Figure 7 45 is a perspective view of the drier board and

arrangement of the block and tackle connected therewith.

Referring to the drawings, 10 denotes an upright box shaped contrivance comprising a long narrow frame having a back board 11, side walls 12 and top piece 13, the front of the frame being open as is the bottom end. The longitudinal upright side walls 12 are each provided adjacent their front ends with grooves or channels 14 which face each other across the front of the box and accommodate the opposite sides of a fixed operating board 15 at the lower end of the device and a sliding drier board or lift 16 throughout the length of the frame above the fixed board 15 and below the top piece 13. In order to insure perfect movement of the drier board 16 adjacent the four corners thereof, rollers 17 are disposed on the upright sides, which rollers bear in the grooves and guide the lift 20 during elevation thereof.

The lift 16 is manipulated by means of a block and tackle 18, one block being carried by the top piece 13, the other being linked to the upper end of the lift, while the cable 19 25 is threaded through both blocks 18 and projects throughout the length of the frame to a pulley or drum 20, about which the cable is wound or unwound to alter the position of the lift, the other end of the cable 19 being 30 brought over the second sheave of the block 18, and then attached to itself.

The drum 20 comprises preferably a flanged spool keyed to a rotary shaft 21 which is supported in a bearing 22 projecting 35 through the mid portion of the fixed board 15 from face to face, as illustratively exemplified particularly in Figure 3. The bearing 22 is provided with a flange 23 disposed over and attached to the rear face of the fixed board 15 between the latter and the flange 40 of the spool 20. The opposite end of the bearing 22 is flush with the front face of the fixed board 15 and the shaft 21 projects there- 45 beyond to receive a toothed ratchet wheel 24 which is keyed to the shaft and provided with an integral collar 25. A housing 26 is disposed over the ratchet 24 and projecting radially and in an upward direction from the housing is an integral cone shaped por- 50

tion 27 within which a pawl 28, in the form of a pin, is guided. The pin at its inner end in the housing is provided with a diametrically disposed block or toe 29 the length of which is greater than the diameter of the pin. The free end of the toe 29 is intended to enter the space between any adjacent teeth of the ratchet wheel 21 to lock the latter against rotary movement. The pin is normally urged in the direction of the ratchet wheel 21 by means of a spring, encircling the pin in the conical portion 27 of the housing and bearing at one end against the shoulders formed by the projecting portions of the toe 29 and at the other against the converging wall of the part 27. The outer end of the cone 27 terminates in a bearing 30 for the pin 28 and is provided with diametrically disposed grooves 31 and 32, one groove 31 being at right angles to the other groove 32 and cut to a substantially greater depth than that of the latter groove 32. These grooves are for the purpose of accommodating a pin 33 projecting transversely through the pawl 28 or pin 28 at a point therein which when supported in the deeper groove 31 permits the toe 29 to engage between the teeth of the ratchet wheel 24, and which when lifted with the pin 28 and turned to rest in the shallower groove 32 the toe 29 is free of the ratchet wheel and allows the same to be rotated in one or the other direction.

Referring to the embodiment of the invention illustrated in Figures 5 and 6, the block and tackle arrangement is substituted by a rack 34 and pinion 35, the latter being keyed to the shaft 21. The rack 34 is connected at its upper end to the sliding drier board 16 by means of a strap 36 which spans an angle guide bar 37 and accommodates the rack 34 during movement thereof. The lower end of the bar 37 is attached to the inner face of the fixed board 15. The rack 34 extends in its operations below the attached end of the bar 37 and its teeth are in mesh with the pinion 35.

Referring now to the drier proper, illustrated particularly in Figures 1 and 2, the board or lift 16 is provided with a bracket 38 projecting from the front thereof, the bracket having at its free end an upright pivot pin 39 about which a second bracket 40 is pivoted. The bracket 40 carries a triangularly shaped frame 41 which in turn supports by means of a brace 43 another frame of the same shape and dimensions and tie bar 44'. The triangular frames 41 and 42 are arranged so that their base angles are uppermost and the apices are directed downwardly. At spaced intervals throughout the length of the sides of the frames are disposed drier bars or rods 44 upon which are hung the clothes to be dried. According to this arrangement, each row of bars 44 is disposed

inside the row immediately above so as to enable all of the bars to support hanging articles without interfering with each other.

In operation, the drier is installed in a room by hanging it against a side wall or by building it into the wall. The box 10 of course is in upright position with the fixed board 15 at the lower end. A crank 45 is attached to the shaft 21 whereby the lift may be lowered by manipulating the pin or pawl 28 to disengage the ratchet wheel 24 and allow free rotary movement of the spool 20 to unwind the cable 19. It will be clear that because of the pivoted support for the drier frame, the same may be adjusted substantially 180 degrees to accommodate any condition of the room and wall space. After hanging the clothes upon the rods, 44, the crank 45 is manipulated to rewind the cable, resulting in the elevation of the board 16 to any desirable height. The pin or pawl 28 is then turned to enable the pin 33 to drop into the deep groove 31 and the toe 29 between adjacent teeth of the ratchet wheel 21, thereby locking the same and holding the lift elevated.

Having now described my invention what I claim and desire to secure by Letters Patent is:

In a wall drier, the combination of an upright guide box having stop members at opposite ends thereof, a pivoted drier frame slidably mounted in said box, and means for supporting, adjusting and holding the frame to any elevation within the limits of the stop blocks, comprising a block and tackle at the upper end of the box attached to the uppermost stop block and a winding drum at the other end of the box to receive the tackle.

In testimony whereof I have affixed my signature.

LOUIS JUDELSON.
